TOY SEWING MACHINE

Filed June 5, 1926

Fig. 1.

Fig. 2.

UNITED STATES PATENT OFFICE

HERBERT ERICH TAUTZ, OF MILWAUKEE, WISCONSIN

TOY SEWING MACHINE

Application filed June 5, 1926. Serial No. 113,882.

My invention relates to improvements in sewing machines and is more especially directed to that type of machine adapted for a child's use.

5 The object of my invention is to provide a simple machine, one that is easily operated and having very few parts to be adjusted.

A further object of my invention is to provide a feeding mechanism to move the material under the usual presser foot.

10 Another object of my invention is to provide a machine having the usual thread looper and its operating shaft, the latter being provided with means for regulating the 15 movement of the material under the presser foot.

In the accompanying drawings,

Figure 1 is a side elevation of my improved machine showing the same as being clamped 20 to a suitable support.

Figure 2 is an enlarged detail view of the bed plate of the machine, the same showing the under side thereof and to which is connected the improved feeding mechanism, and

25 Figure 3 is a detail view taken on the line 3-3 of Figure 2.

Referring to the accompanying drawings in detail, wherein like reference characters denote corresponding parts throughout the 30 several views, the numeral 1 indicates the base of my improved machine, the same being formed of suitable material, preferably wood, and having hingedly connected thereto a bed plate 2 formed of sheet metal 35 and provided with downturned marginal flanges 3. The base 1 is provided in its front wall with an opening 4 in which is receivable the free end of a clamp 5, the same being adapted to securely clamp the base 1 40 upon a suitable support 6.

As disclosed in the drawings, the upper face of the bed plate 2 is substantially flat throughout its entire length and has secured thereto at one end the usual goose-neck arm 45 7, the same having mounted therein a driving shaft 8 which is adapted to be rotated by a hand wheel 9, or any suitable driving means. The other end of the drive shaft 8 has connected thereto the usual mechanism for reciprocating the needle bar 10.

Secured to the drive shaft 8 is a belt pulley 11 around which passes a belt 12, preferably of a flexible nature, the same further engaging a belt pulley 13 secured to one end of a looper shaft 14 carried upon the under face 55 of the bed plate 2.

As disclosed in Figure 2, it will be noted that the bed plate 2 has provided therein at one end an opening 15 under which the belt pulley 13 is positioned. The looper shaft 14 60 is mounted within an arm 16 formed integral with the bed plate 2 and bent downwardly at right angles therefrom, the lower end of which is bifurcated and has positioned therein a bearing 17 through which the shaft 14 65 passes.

The other end of the bed plate 2 is provided with a pair of spaced transversely extending slots 19 and 20 in which the material feeder 21, hereinafter more fully described, 70 is adapted to move. That portion of the bed plate 2 which lies between the slots 19 and 20 is provided with an opening 35 for the passage of the needle therethrough during its operating strokes.

75 As disclosed in Figure 2, it will be noted that the under face of the bed plate 2 has detachably secured thereto a circular plate 22, the central portion of which is provided with a cutout portion 23. The plate 22 has formed integral therewith a downwardly extending arm 24, the intermediate portion of which is provided with a horizontally arranged slot 25 which receives therein one end of a feeding mechanism 21, the other end of which is retained against lateral movement by a pair of downwardly extending fingers 26 which are likewise formed integral with the ring 22.

80 The feeding mechanism 21 is composed of a body portion 21' having ends 37 and 38 which are connected by spaced arms 39 and 40 which are receivable within the slots 19 and 20. As disclosed in Figure 3, it will be noted that the arms 39 and 40 are struck upwardly so that the horizontal plane of their upper faces are above that of the body 21'.

85 To reciprocate the feeding device within the slots 19 and 20, I have provided an arm 100

27 which is formed integral with the body portion 21' of the feeder, the free end of which has provided therein an enlarged opening 28 which is adapted to receive an eccentric block 29, detachably secured to the looper shaft 14 by the locking screw 30. To support the adjacent end of the shaft 14, the plate 22 has formed integral therewith a downwardly extending arm 31 in which is positioned a bearing 32 for the reception of the shaft 14.

10 As disclosed in Figure 3, the end of the looper shaft 14 is provided with a transverse slot for the reception therein of the usual looper, not shown in the drawings, but clearly understood by those skilled in the art.

15 The bed plate 2, as previously mentioned, is hingedly connected to the base 1 and to lock the same thereupon I have provided upon the under face of the bed plate 2 a pair of downwardly extending resilient fingers 33, the lower ends of which are provided with enlarged portions adapted to be received within a groove extending along 20 the inner face of the base 1. As further disclosed in Figure 2, it will be noted that one of the resilient fingers 33 is positioned under the plate 22 and retained to the plate 2 by the securing means for the plate 22.

25 30 Having thus briefly described my invention, I will now endeavor to explain its operation.

Upon the rotation of the hand wheel 9, 35 rotary movement will be imparted to the looper shaft 14 and upon the rotation of the latter the feeding mechanism will be moved back and forth within the slots 19 and 20 for the purpose of moving the material across the bed plate 2. This movement is accomplished through the shaft 14, the eccentric 40 29 and the arm 27, which is formed integral with the feeder 21.

45 From the foregoing, it is thought that the construction, operation and many advantages of the herein described invention will be apparent to those skilled in the art, without further description, and it will be understood that various changes in the size, shape, proportion and minor details of construction 50 may be resorted to without departing from the spirit or sacrificing any of the advantages of the invention.

Having thus fully described my invention, what I claim as new, and desire to secure by Letters Patent, is:—

60 In a machine of the class described, the combination of a bed plate having mounted thereon a needle operating means including a rotatable shaft, a plate detachably connected to the under face of said bed plate and forming a support for a material feeder, said feeder including an elongated strip of metal having its intermediate portion slotted to provide spaced arms, said arms being bent 65 upwardly for movement within slots pro-

vided in the bed plate, a depending arm formed integral with said feeder and eccentrically connected to said shaft, said feeder having one end supported for reciprocatory movement and the other for vertical movement in elements formed integral with said support plate, and said feeder adapted to reciprocate transversely of the bed plate to feed the material thereon upon the movement of the shaft.

70 75 In testimony whereof I affix my signature.

HERBERT ERICH TAUTZ.
